UNITED STATES PATENT OFFICE

112,609

DESIGN FOR A BIRD CAGE

Earl W. Little, Indianapolis, Ind.

Application May 24, 1938, Serial No. 77,354

Term of patent 3½ years

To all whom it may concern:

Be it known that I, Earl W. Little, a citizen of the United States, residing at Indianapolis, in the county of Marion and State of Indiana, have invented a new, original, and ornamental Design for a Bird Cage, of which the following is a specification, reference being had to the accompanying drawing, forming part thereof, the front and back portions of the cage being

substantially identical in configuration and appearance.

Figure 1 is a perspective view and Figure 2 a top plan view of a bird cage, showing my new design.

I claim:

The ornamental design for a bird cage, as shown and described.

EARL W. LITTLE.
